UNITED STATES PATENT OFFICE

LE ROY E. BARINGER, OF WEBBER, KANSAS

FENCE STAPLE APPLYING TOOL

Application filed July 3, 1930. Serial No. 465,707.

This invention relates to a hand tool for applying wire staples to T-shaped or any flat sided steel or iron fence posts to secure the wire or other similar fencing material in position upon the posts.

The invention particularly contemplates providing a combination tool of the kind described above which will have means to positively position and retain staples to be applied between the jaws thereof and to clamp the staples to conform to the contour of the fence post in clamping relation thereto, and combining means incorporated in and attached to said tool capable of performing all of the commonly required operations in erecting this type of fence, which operations ordinarily require a plurality of separate tools and often the services of more than one person at each fence post.

The main object of the invention is to provide an efficient device of the character described well fitted for the purposes for which it is made, saving of labor, of time, and material used in performing its operation. This device will do a quicker, easier and neater job and the wires are more securely mounted thereby by the staples fixed to the post by means of the invention. Incorporated and associated with the tool are ordinary wire cutters and laterally protruding staple cutting means, and means for loosening staples from the post when desired, gripping jaws for holding wire, and means to use the tool as a wire tightener or stretching handle.

Reference to the accompanying drawings and the explanation thereof below will enable anyone acquainted with this art to derive a clear understanding of the combination of the device and its parts and the operation thereof.

In the drawings:—

Figure 1 is a longitudinal side view.

Figure 2 is an end view from the jaws of the device.

Figure 3 is a cross section of Figure 1 on the line 3—3.

Figure 4 is a view of one of the legs of the plier members.

Figure 5 is a view of one of the wire staples. 50
Referring in detail to the drawings:—

Figure 1 represents generally a tool of the character described comprising legs 3—3 pivoted as at 1 and actuated by a spring 1a of any desired type to have an action of pressing said handles together and maintaining jaws 2—2 at the ends of said legs in abutting relationship. The jaws 2 have notches 4 and cut out portions 5 as seen in Figure 2 to accommodate a bent wire staple of the general type shown in Figure 5 and indicated by the reference numeral 12.

The leg or handle part 3 is formed with an outwardly curved part 6 on the enlarged part of the handle through which the pivot 1 passes. This part 6 is formed with a curved forward face 15 the inner part of which is provided with a groove 5 and a reduced part 16 connects each jaw 2 with the outer part of the forward face 15 so that this reduced part 65 16 forms a notch or space between the outer part of the base 15 and the inner face of the jaw 2.

Each jaw 2 curves inwardly from its outer end to its inner end and as the inner part of each jaw extends inwardly well beyond the inner edge of the reduced part 16 a space is formed between the inner part of the jaw and the inner part of the face 15, the outer wall of the space being formed by the inner 75 80 end of the parts 16.

The inner end of each jaw slopes from the outer edge to the inner edge in a direction toward the outer end of the jaw and this sloping end is formed with the notch 4. The parts 6 are so formed that the jaws 2 are slightly out of alignment with each other as shown in Fig. 2, so that the notches are offset or out of alignment and this arrangement holds the staple 12 in the diagonal position 85 90

when the bent ends of the staple are placed in the notches 4 so that the staple can bridge a fence wire placed on the post 11, with one limb of the staple arranged below the wire 5 and the other limb arranged above the wire.

A staple such as shown at 12 in Fig. 5, is placed between the jaw part of the tool with portions of the staple adjacent the grooves 5, and the bent ends engaging the notches 4. 10 As the spring 1a tends to hold the tool in closed position, the staple will be clamped between the jaw parts so that the staple can be readily placed against the post and the wire passes across the same by simply placing the jaw part of the tool around the post as shown in Fig. 1.

The handles 3 are then pressed together so as to cause the jaw parts of the tool to press the staple into firm engagement with the 20 post as shown in dotted lines in Fig. 1.

The tool may be provided with the usual wire cutting notches 8, the gripping notches 10 and it may also be provided with the staple cutting projections 9 having the 25 notches 7 therein, these projections being so arranged that when the tool is opened, the notches 7 in the projections will aline, so that a staple or a piece of wire can be placed in the notches, and then by forcing the handles 30 3 together the projections will move away from each other and thus cut the staple or wire.

The free ends of the handles 3 are also formed with the recesses 3a in their inner 35 faces, and these ends are substantially wedge-shaped, so that each free end of the handles can be used for removing a staple from the fence post by forcing said end between the end of the staple and the post and then prying 40 the staple from the post. One of the handles can also be provided with a hole 14 for use as a wire wrapper by placing the ends of a number of wires in said opening and then turning the tool to cause the ends of the wires 45 to be twisted together.

It is thought from the foregoing description that the advantages and novel features of the invention will be readily apparent.

It is to be understood that changes may be 50 made in the construction and in the combination and arrangement of the several parts, provided that such changes fall within the scope of the appended claims.

What is claimed is:—

55. 1. A tool of the class described comprising a pair of members pivotally connected together and each comprising a handle part and a jaw part, each jaw part being substantially U-shaped with the beaks extended toward each other; the end of each beak having a notch therein for engaging an end of a staple placed between the jaw parts and those portions of the walls of the jaw parts opposite the beaks having grooves therein 60 to receive parts of the staple, the notched 65 ends of the beaks being offset laterally from each other whereby the staple is held in a diagonal position to bridge the fence wire placed on a post and which the staple is adapted to hold on the post when the staple is pressed into engagement with the post by the tool.

70 2. A tool of the class described comprising a pair of members pivotally connected together and each including a handle part and a jaw part, each jaw part including outwardly curved portions, the forward face of which is curved and the inner portion of the face having a groove therein, a connecting member connected with the outer part of said curved face, and a plate-like member having its outer end fastened to the said connecting part, the plate-like member curving slightly inwardly from its outer end to its inner end with the inner part of said 75 plate-like member extending inwardly beyond the connecting member, the inner end of each plate-like member having a notch therein for engaging an end of a staple between the jaw members with parts of the staple engaging the grooves, the notched ends of the plate-like members being offset laterally from each other whereby the staple is held in a diagonal position to bridge a fence wire placed on a post and which the 80 staple is adapted to hold on the post when the staple is pressed into engagement with the post by the tool.

85 2. A tool of the class described comprising a pair of members pivotally connected together and each including a handle part and a jaw part, each jaw part including outwardly curved portions, the forward face of which is curved and the inner portion of the face having a groove therein, a connecting member connected with the outer part of said curved face, and a plate-like member having its outer end fastened to the said connecting part, the plate-like member curving slightly inwardly from its outer end to its inner end with the inner part of said 90 plate-like member extending inwardly beyond the connecting member, the inner end of each plate-like member having a notch therein for engaging an end of a staple between the jaw members with parts of the staple engaging the grooves, the notched ends of the plate-like members being offset laterally from each other whereby the staple is held in a diagonal position to bridge a fence wire placed on a post and which the 95 staple is adapted to hold on the post when the staple is pressed into engagement with the post by the tool.

In testimony whereof I affix my signature.

LE ROY E. BARINGER.
